HOUSING FOR A CEILING HEATER

George D. Hart, Cincinnati, Ohio, assignor to Nutone,
Inc., Cincinnati, Ohio, a corporation of New York

Filed Mar. 30, 1960, Ser. No. 59,962

Term of patent 14 years

(Cl. D81—10)

FIGURE 1 is a perspective view of a housing for a ceiling heater showing my new design.

FIGURE 2 is a cross sectional view taken on the line 2—2 of FIGURE 1.

I claim:

The ornamental design for a housing for a ceiling heater, substantially as shown.
